UNITED STATES PATENT OFFICE.

THOMAS H. BIBBY, OF DENVER, COLORADO.

ACETYLENE-GAS LAMP.

1,277,286.

Specification of Letters Patent. Patented Aug. 27, 1918.

Application filed June 22, 1917. Serial No. 176,418.

To all whom it may concern:

Be it known that I, THOMAS H. BIBBY, a citizen of the United States, residing at Denver, in the county of Denver and State of Colorado, have invented certain new and useful Improvements in Acetylene-Gas Lamps; and I do hereby declare the following to be a full, clear, and exact description of the invention, such as will enable others skilled in the art to which it appertains to make and use the same.

This invention relates to improvements in acetylene gas lamps of the portable type and has for its primary object to provide a lamp structure embodying several independently operable generators for supplying acetylene gas to a common burner whereby the supply of carbid may be alternately replenished in the holders while the lamp is in operation.

Another object is the provision of means for controlling the admission of water to the carbid holders and for deflecting the liquid into the ports or passages of the respective holders.

Another object is the provision of a novel type of guard or shield adjustably supported on the burner tips for protecting the latter and preventing the flame from being blown out by wind or swift air currents.

With these and other objects in view, the invention consists in the novel construction, combination and arrangement of parts as will be hereinafter specifically described, claimed and illustrated in the accompanying drawing, in which:

Figure 1 represents a front elevation of the improved lamp,

Fig. 2 represents a side elevation thereof partly in section,

Fig. 3 represents a fragmentary perspective view of the reflector, burner tip and guard therefor,

Fig. 4 represents a plan view of the lamp, partly in section, the top portion carrying the water chamber and burner tip being removed,

Fig. 5 represents a detail sectional view through the upper part of the lamp, and,

Fig. 6 represents a perspective view of the preferred type of holder for the lamp.

Referring to the drawing in detail, wherein similar reference numerals designate corresponding parts throughout the several views, the numeral 5 indicates a hollow cylindrical holder having both ends open and externally threaded to receive the closure

caps 6 which are removably fitted thereon. A vertical partition 7 is arranged centrally within the holder 5 dividing the interior of the latter into two carbid-receiving chambers 8, each of which is provided with a port 8^a. The upper central part of the cylindrical holder 7 is connected with the vertical hollow extension 9, having a reduced and threaded upper terminal 10 defining an inclined shoulder 11 constituting an abutment for a packing gasket 12. The upper part of the lamp, designated generally by the numeral 13, is of hollow construction, providing the internal water chamber 14 having communication with a filling opening which is closed by a hinged cap 15. The water chamber 14 communicates with a depending extension 16, receiving the stem 17 of a valve 18, which latter is adapted to engage the lower edge of the tubular extension 16 to regulate or cut off the flow of water therethrough. The upper terminal of the stem 17 is threaded in the top part of the lamp and is detachably connected with a turning key 19, whereby the stem may be conveniently rotated to properly adjust the valve 18 and thus regulate the flow of water to the holder 5.

A rectangular water receiver 20 is secured upon the boss 21 formed upon the top part of the holder 5 within the extension 9 and surround the passage or port 22 communicating with the two carbid-receiving chambers 8 in the holder. Deflecting plates 23 are pivotally supported on pins 24 secured in the receiver 20 and are actuated, in a manner to be hereinafter described, to control the passage of water to the chambers 8 and direct it into the desired passage 22 by which it is conducted to the carbid-receiving chamber 8.

Slide valves 25 are mounted for longitudinal movement in the slot 26 formed in the top part of the holder 5 and the outer terminals of the valves are turned upwardly, as indicated at 27, to provide handles for convenience in adjusting the valves. The slot 26 intersects the passage 22 and the valves 25 may be adjusted independently to regulate the flow of water through the ports 8^a and into the respective chambers 8, or, if desired, to completely cut off the flow of water thereto.

The acetylene gas generated in the chambers 8 is conducted to the interior of the extension 9 by the passages 8^a and 22 and

finds its way into the gas pipe 27, which is arranged in the top part 13 of the lamp and projects through the concaved reflector 28 secured to the front wall thereof. A perforated plate 29, preferably of cylindrical formation, is detachably secured to the depending extension 16 and supports a wad of fibrous material 30 under the bottom wall of the top part 13, so as to prevent particles 10 of carbid or other granular substances from entering the pipe 27 and obstructing the discharge port of the burner tip 31.

A tubular guard or shield 32 is slidably and rotatably fitted upon the burner tip 31 15 and is frictionally held against accidental displacement thereon. The guard is formed with several circular series of relatively small apertures 33, which admit air to the interior thereof to support the combustion 20 of the gas issuing from the discharge port 34 in the burner tip. Under normal conditions, the guard 32 may be moved rearwardly against the deflector 28 and in this 25 position the front edge thereof terminates in proximity to the front end of the burner tip 31. However, when the lamp is subjected to swift air currents, the guard 32 may be moved outwardly to the approximate position 30 illustrated in Fig. 3, so as to protect the flame from the direct action of the air and thus prevent it from being blown out.

The opposed sides of the top part 13 of the lamp are provided with loops or rings 35 which project laterally and are adapted 35 to be engaged in the hook terminals 36 of a substantially U-shaped supporting member 37. The web portion of the member 37 is twisted to provide a loop 38, having connection with a link 39 and a substantially 40 T-shaped member 40. A ring 41 is swivelly mounted upon the T-shaped member 40 and is provided with a loop 42 pivotally receiving a supporting hook 43 adapted to be utilized in suspending the lamp from an object. The rear wall of the top part 13 is also provided with a supporting hook 44 to be used in supporting the lamp upon the cap of a miner.

The lower terminals of the plates 23 are 50 engaged by the slide valves 25, so that when the right hand valve is closed, as shown in Fig. 5, the plate 23 engaged therewith is swung inwardly to an inclined position and thus directs the water from the extension 55 16 into the left hand port 8^a.

What I claim is:—

1. In an acetylene gas lamp, a carbid

holder, a partition arranged in the holder dividing the interior of the latter into carbid receiving chambers, a water receiver 60 communicating with said chambers, means for supplying water to the receiver, means for alternately directing the water from the supplying means into the respective chambers, and means for controlling the admission of water to the chambers and actuating the directing means.

2. In an acetylene gas lamp, a carbid holder, a partition arranged in the holder dividing the interior of the latter into carbid-receiving chambers, means for supplying water to said chambers, means for controlling the admission of water to the chambers, and means actuated by the controlling means to direct the water into the respective 75 chambers.

3. In an acetylene gas lamp, a carbid holder, a partition arranged in the holder dividing the interior of the latter into carbid-receiving chambers, a water receiver 80 communicating with the chambers, means for supplying water to said receiver, means for controlling the admission of water to the respective chambers, and means actuated by the controlling means to direct the water 85 into the respective chambers.

4. In an acetylene gas lamp, a carbid holder, a partition arranged in the holder dividing the interior of the latter into carbid-receiving chambers, means for supplying 90 water to said chambers, means for controlling the admission of water to the respective chambers, and hinged deflector plates actuated by the controlling means to direct the water into the respective carbid-receiving 95 chambers.

5. In an acetylene gas lamp, a carbid holder, a partition arranged in said holder dividing the interior of the latter into carbid-receiving chambers, a water receiver 100 communicating with the chambers, means for supplying water to said receiver, means for controlling the admission of water to the respective chambers, and pivoted deflector plates arranged in the receiver and actuated by the controlling means to direct the water into the respective carbid-receiving 105 chambers.

In testimony whereof I affix my signature in presence of two witnesses.

THOMAS H. BIBBY.
